Primary Examiner — Robert M Spear*(74) Attorney, Agent, or Firm* — Foley & Lardner LLP**CLAIM**

We claim the ornamental design for a fitment for interconnection between product packaging and a product dispenser, as shown and described.

DESCRIPTION

FIG. 1 is a top, front, right perspective view of the claimed design;

FIG. 2 is a bottom, rear, left perspective view thereof;

FIG. 3 is a rear elevation view thereof;

FIG. 4 is a front elevation view thereof;

FIG. 5 is a right elevation view thereof;

FIG. 6 is a left elevation view thereof;

FIG. 7 is a top plan view thereof; and,

FIG. 8 is a bottom plan view thereof.
